UNITED STATES PATENT OFFICE

126,455

DESIGN FOR A DRESS ENSEMBLE

Jack Herzog, New York, N. Y.

Application January 11, 1941, Serial No. 98,000

Term of patent 3½ years

To all whom it may concern:

Be it known that I, Jack Herzog, a citizen of the United States, residing in New York city, in the county of New York and State of New York, have invented a new, original, and ornamental Design for a Dress Ensemble, of which the following is a specification, reference being had to the accompanying drawings, forming part thereof, in which—

The characteristic feature of my design resides in the combination on the dress ensemble disclosed of the specific jacket member having corded trimming around the outer edges thereof in association with the specific harmonizing fastening elements down the front, as shown.

I claim:

The ornamental design for a dress ensemble, as shown and described.

JACK HERZOG.
